CLOSURE FOR NONREFILLABLE BOTTLES
OR OTHER CONTAINERS

Oliverio Agüero Soto, Habana, Cuba

Application March 8, 1945, Serial No. 581,592

2 Claims. (Cl. 215—22)

1

This invention relates to closures for non-refillable bottles or other containers, and it has for its object to provide an improved closure that will allow the free passage of the contents therefrom but will prevent refilling after the contents of the container is exhausted.

Another object of the invention is to provide a closure for non-refillable bottles or other containers, that can be easily and expeditiously secured to the bottle or container, which cannot be removed therefrom without breaking or damaging the means permanently securing the closure to the bottle or container.

A further object of the invention is to provide a closure for non-refillable bottles or containers, that will guarantee the genuineness of the contents thereof and retain same free from contamination until completely exhausted, which is neat and simple in construction, inexpensive to manufacture by reason of the minimum of the elements composing same, and perfectly efficient in operation.

This invention will be described with reference to the figures of the accompanying drawings, of which:

Fig. 1 is a diametral vertical section view of the closure applied to a bottle neck in upright position.

Fig. 2 is a view similar to Fig. 1, showing the bottle neck inverted for pouring the contents therefrom and through the closure.

Fig. 3 is a sectional view taken on the line A—A of Fig. 1.

Fig. 4 is a top plan view of the loose valve operating within the closure.

Fig. 5 is an elevation of the valve.

Fig. 6 is an elevation of the disc which forms a seat for the semi-spherical lower portion of the valve.

Fig. 7 is a diametral sectional view of the closure applied to a bottle neck in horizontal position.

In the drawings, the numeral 1 indicates the neck of a bottle wherein there is inserted a hollow cylindrical body 2 which may be formed from glass or a plastic material and which has its lower end open and provided with inner threads 3 and its upper end 4 closed and of a diameter slightly greater than that of the lower open end. Said upper end 4 is provided at its outer surface about its line of greater diameter with relation to the rest of the body 2, with an annular flange 5 upon which is disposed an apertured rubber washer 6 upon which is fitted a metallic cap 22 which permanently secures the closure to the bottle neck and beneath said an-

2

nular flange 5 there is provided another annular apertured washer 7 through which said annular flange 5 seats upon the mouth or upper end of the bottle. Said upper end 4 has at the middle portion of its outer side surface a flattened area having centrally arranged thereon an opening 8 and an exteriorly threaded nipple adapted to act as an outlet for the contents of the bottle.

Said hollow cylindrical body 2 is tapered from opening 8 to a point near its lower open end and has formed at a certain height of its inner wall inter-spaced tooth-shaped projections 9 adapted to serve as stops for a pellet 10 which is preferably formed from glass or metal or an alcohol-proof material. Said pellet 10 is loosely disposed between said projections 9 and the top portion of a valve 11 which is loosely inserted within the lower threaded end of cylindrical body 2. On the innerly threaded lower open end of body 2 there is screwed an innerly conical disc 12 which is reduced in half of its lower surface and has centrally formed on its upper surface an outerly threaded nipple 21 having its upper edge burnished to a semi-spherical contour, said nipple 21 being adapted to act as a seat for the valve 11.

The lower open end of body 2 has formed in its inner wall and near its edge an annular recess 14 having formed therewith four inter-spaced tooth-shaped projections 15 and above said annular recess 14 there are suitably formed four other inter-spaced tooth-spaced projections 16, all said projections serving to guide the valve 11 in its movement within the lower open end of body 2.

The closed end 4 of body 2 has formed in its side opposite the liquid outlet opening 8 an air inlet opening 13 extending vertically within the wall of body 2 and ending in the annular recess 14.

The valve 11 consists of a burnished cylindrical member having its top portion open and its bottom portion closed in a semi-spherical shape having centrally formed therein a hole and arranged thereon an outer nipple 17, said valve having laterally formed therein two opposed square openings 19. Within the semi-spherical end of valve 11 there is disposed a piece of cork or other floatable material 18 whose upper edge reaches near the upper edges of openings 19 the cork or other floatable material being recessed at its edges, such recesses or slots coinciding with said upper ends of openings 19, so that liquid may flow through the openings 19 into the interior of the valve body 11, as will be more specifically pointed out and described hereinafter.

In the top open end of valve 11 there is pressure fitted a rectangular member 20 which is adapted to serve as a stop for the cork piece 18 and also as a seat for the pellet 10, said rectangular member 20 having a small perforation at the middle portion of its upper surface.

The closure of this invention is secured to the neck of the container by means of an annular metallic cap 22 having centrally formed in its upper plane surface an opening through which protrudes upwardly the upper end of body 2, the side edges of said cap being of a suitable length so that pressure on said side edges will cause same to be tight against and beneath the outer flange of the bottle neck 1.

The operation of this closure is as follows: When it is desired to pour the contents of the container, it is tilted from its upright position to the position shown in Fig. 2. When so arranged the air entering through air inlet 13 will allow the contents to pass freely through the central opening of the disc 12 into the annular recess 14 through the spaces provided by the projections 15, whereupon the liquid will displace the valve 11 onward at the same time that the pellet 10 drops on the projections 9. The liquid then flows through the opposed lateral square apertures 19 of the valve 11 and through the two openings into which the upper open end of the valve 11 is divided by the rectangular piece 20 fitted therein, and the liquid also flows in a smaller amount through the spaces provided between the projections 16. Finally the liquid passes through the spaces between the projections 9 and the remaining portion of the body 2, to find its way out through the discharge outlet 8.

It is evident that an attempt to inject liquid into the bottle through outlet nipple 8 of the closure in the normal or upright position of the bottle will be futile, by reason of the fact that the valve 11, with the aid of the weight of pellet 10 which normally rests on the top portion of the valve, will normally rest on the burnished edge of the nipple of disc 12 wherethrough the liquid to be poured enters into the closure, and the pressure exerted by the liquid being injected into the closure will force the valve 11 on its seat and the pellet 10 upon the valve, whereupon the liquid upon being prevented from passing down into the bottle will tend to find its way out through air inlet opening 13.

Similarly, liquid cannot be injected into the closure in the horizontal position of the bottle as shown in Fig. 7, due to the fact that by reason of the conical shape of the inner wall of the body 2, the pellet 10 normally tends to run to its resting position on the valve 11 and to force the valve 11 on its seat formed on the disc 12 wherethrough the liquid to be discharged flows into the closure, whereupon the liquid will be prevented from flowing into the bottle and will find its way out through the air inlet opening 13.

If an attempt should be made to force liquid into the closure in the tilted position of the bottle shown in Fig. 2, the valve, due to the floating nature of the cork enclosed therein, will ascend as the liquid enters into the closure, until it fits against the disc 12 which normally acts as the valve seat, whereby the liquid will be prevented from entering into the bottle and compelled to find its way out through air inlet opening 13.

It is evident that in any position of the bottle, if an attempt should be made to inject liquid into the closure by obturating either the air inlet or the liquid discharge openings, the very pressure

of the liquid injected will force the valve on its seat.

Obviously changes may be made in the construction details and in the arrangement of the closure parts, without thereby altering the essential character of the invention which is such as claimed hereinafter.

What I claim is:

1. A closure for non-refillable containers, comprising, in combination with a container, a hollow cylindrical body adapted to rest through a washer on the upper end of the container and provided with air inlet and liquid outlet openings and with an annular recess interiorly of its lower end, a metallic cap that inviolably secures said hollow cylindrical body to the upper end of the container through a washer, a cylindrical valve loosely disposed within said hollow cylindrical body and slidably therein, and which is open above and closed below and ends in a semi-spherical portion having centrally arranged therein and formed therewith an outer nipple, a portion of a floatable material disposed within said semi-spherical portion of the valve, guiding means for said valve in its movement within said hollow cylindrical body, a seat for said valve, a pellet loosely disposed within said hollow cylindrical body and adapted to normally rest on the top of said valve, and means for limiting the run of said pellet within said hollow cylindrical body.

2. A closure for non-refillable containers, comprising, in combination with a container, a hollow cylindrical body having its top end closed and its bottom end open and provided with inner threads, said top end being of a larger diameter than said bottom end and having a side opening for liquid discharge and thereon arranged an outer nipple and a side air inlet disposed oppositely to said liquid discharge opening, said air inlet opening extending vertically within the wall of said hollow cylindrical body and ending in an enlarged annular recess formed in the proximity of its lower edge, and said hollow cylindrical body having at a point of its upper portion an outer annular flange adapted to rest on the upper end of the container through a washer, a pellet loosely disposed within said hollow cylindrical body, a cylindrical valve loosely and slidably disposed within said hollow cylindrical body and having its upper end adapted to serve as a seat for said pellet, said valve having its upper end open and its lower end closed and ending in a semi-spherical shape carrying at its outer middle portion a nipple, and said valve having two opposed side openings and enclosing within its semi-spherical lower end a portion of a floating material that assures the valve flotation, a rectangular piece having a hole centrally formed in the middle portion of its upper surface, said rectangular piece being dapted to be pressure fitted on the upper open end of said valve, pluralities of tooth-shaped projections suitably formed in the inner wall of said hollow cylindrical body and adapted to serve as guides for said valve and as stops for said pellet, a conical disc reduced in half of its lower surface and having a centrally disposed hole extending therethrough, and said disc provided with a nipple having outer threads and a burnished edge, said disc being adapted to be screwed in the inner lower threaded end of said hollow cylindrical body, the nipple of said conical disc being adapted to serve as a seat for the semi-spherical lower portion of said valve, and a metallic annular cap adapted to inviolably secure said hollow cylindri-

cal body to the upper end of the container through a washer.
